UNITED STATES PATENT OFFICE

JOSEPH F. MORAN, OF WATERBURY, CONNECTICUT, ASSIGNOR TO SCOVILL MANUFACTURING COMPANY, OF WATERBURY, CONNECTICUT, A CORPORATION OF CONNECTICUT

FLASH LIGHT SWITCH

Application filed June 10, 1931. Serial No. 543,334.

This invention relates to electric flashlights of the portable or hand type and more particularly to a current-controlling switch especially adapted for flashlight use.

5 An object of this invention is to provide an improved form of slide switch for flashlights constructed and arranged to permit selective flashing or permanent lighting of the lamp and to prevent accidental operation 10 of the lamp at any time.

These and other objects which will be apparent to those skilled in this particular art are accomplished by means of the invention illustrated in the accompanying drawing in 15 which,

Fig. 1 is a partial sectional view of a flashlight constructed in accordance with one embodiment of this invention, showing the parts in inoperative position.

20 Fig. 2 is a similar view of the switch mechanism showing the slide in position for permanent lighting, and

Fig. 3 is a similar view showing the position of the slide when in position to close 25 the circuit for flashing purposes.

The particular embodiment of the present invention which has been chosen for illustration is shown in connection with a flashlight having the usual casing 5 housing a battery 6 and having a lamp 7 mounted in a socket 8 at one end of the casing. One battery terminal is electrically connected through the casing, or by other means, with one terminal of the lamp 8, while the center terminal 9 of the lamp contacts with a conductor strip 10 forming part of an assembly which includes a separate conductor strip 11 in contact with the center terminal of the battery 6. Strips of insulation 12 and 13 form a part 30 of the conductor strip assembly for insulating the conductors from each other and from the metallic casing 5, and the assembly is suitably mounted in position in any desired manner, all as more fully described in the 35 co-pending application of Morris H. Bennett, Serial Number 520,538, filed March 6, 1931. As therein described, the insulating strip 13 intermediate the conductor strips terminates short of the free ends thereof so 40 as to provide uninsulated portions 14 and 15

which are spaced from but closely adjacent each other. It will be apparent that a slight movement of the strip 14 toward the strip 15 will move the same into contact and close the circuit between the battery and lamp. 55

In the present application, the mechanism for controlling the lamp circuit is in the form of a slide switch supported upon an escutcheon plate 16 secured to the casing 5 over an opening 17 adjacent the free end of the conductor strip 14. A thumb piece 18 is slidably positioned on the escutcheon plate and secured thereto by ears 19 extending through slots of the usual type, not shown, and engaging the under surface of the escutcheon plate, the slidable thumb piece being positioned over an opening 20 in the face of the escutcheon plate. Movable with the thumb piece in the opening 20 is a ball 21, such as a standard ball bearing, positioned 70 in a depression in the thumb piece and adapted to seat in a pocket 22 formed in a flexible depressible member 23 secured to the casing and positioned so that the portion formed by the curve of the pocket 22 bears 75 on the strip of insulation 12 adjacent the free end of the conductor strip 14. The outer free end of the flexible depressible member 23 adjacent the pocket is formed 80 with a substantially flat surface 24 upon which the ball 21 is adapted to ride when the slide 18 is forced in that direction, see Fig. 2, so that the strip will be held in depressed position when the slide is so moved 85 and the conductors 14 and 15 will be held in permanent contact to provide a constant flow of current through the lamp 7. Movement of the thumb piece 18 in the opposite direction, as shown in Fig. 3, causes the ball 21 to cam against the surface of the flexible member at the opposite side of the pocket. The arrangement is such, however, that the ball 90 will not ride entirely out of the pocket with the result that upon release of the thumb member 18 by the operator, the resilience of the depressible member 23 causes the ball to return to the center of the pocket 22 and permit the conductors to separate as shown in Fig. 1. The extent of movement of the slide 95 in either forward or rearward direction can 100

be determined by the length or relative position of the slot 20 in which the ball rides, or by the slots through which the ears 19 extend.

5 The operation of the flashlight will be apparent. The inoperative position is shown in Fig. 1 in which the ball 21 is seated in the pocket 22 of the flexible depressed member 23, and the parts are normally held in this 10 position, in which the lamp circuit is open, by the resilience of such member. If a permanent light is desired, the slide is pressed by the thumb of the operator into the forward position shown in Fig. 2. In this position the ball 21 has ridden out of the pocket on to the surface 24, as a result of which the flexible member 23 has been depressed and the exposed portions of the conductor strips moved into contact so as to close the lamp 15 circuit. The surface 24 being substantially flat, the parts are held in this position independently of the operator. To return the parts to the inoperative position, it is necessary for the slide 18 to be manually returned 20 to the position shown in Fig. 1. If flashing operation of the lamp is desired, the slide 18 is moved in a rearward direction to the position indicated in Fig. 3, in which position the flexible member 23 has again been de- 25 pressed by the ball riding up the rear surface of the pocket 22 and the conductors are again moved into contact. In this position, however, the ball is not moved entirely out of the pocket 22 so that it is necessary for the operator to hold the slide in the rearward position as long as a light is desired. Upon release of the slide or thumb piece 18, the upward pressure of the flexible member 23 causes the ball 21 to roll back into the pocket 30 22 and the parts are automatically returned to the inoperative position shown in Fig. 1.

Although the present application shows a switch in which the slide member is moved forwardly to permanent lighting position and rearwardly to flash, it will be apparent that the arrangement is such as to permit the parts being designed so that the slide will move rearwardly to permanently light the lamp and forwardly for flashing, if desired.

50 It will also be apparent that operation of the switch to close the lamp circuit can occur only upon intentional sliding movement of the thumb piece 18 in one direction or the other. No depressible movement of the slide 55 can occur and inward pressure upon the thumb piece 18 will have no effect whatever as far as the lamp circuit is concerned.

I claim as my invention:—

1. The combination in a flashlight having 60 a casing, a lamp, and a battery, of a switch mechanism for controlling the flow of current through said lamp including a movable member for closing the lamp and battery circuit and a thumb piece slidably mounted on 65 said casing for actuating said member, the

thumb piece engaging surface of said member being formed to hold the slide in circuit closing position when said slide is moved in one direction and to return said slide to inoperative position when moved in the other direction. 70

2. The combination in a flashlight having a slotted casing, a lamp and a battery, of a switch mechanism for controlling the flow of 75 current through said lamp including a pair of conductors, means for moving said conductors into current carrying engagement including a thumb piece slidably mounted on said casing and an intermediate flexible member adapted to be actuated by said slide for moving one of said conductors into engagement with the other, the engaging surfaces between said member and said slide being formed to provide a constant light when said slide is moved in one direction and to provide 80 for flashing of said light when said slide is moved in the other direction. 85

3. The combination in a flashlight having a slotted casing, a lamp, and a battery, of a switch mechanism for controlling the flow of 90 current through said lamp including a thumb piece slidably mounted on said casing, and a co-operating flexible member having a pocket formed therein, means movable with said thumb piece and adapted to normally seat in 95 said pocket to permit said member to assume an inoperative position, and means for determining the extent of movement of said thumb piece in each direction to permit said pocket engaging means to be moved entirely out of 100 said pocket when said thumb piece is forced in one direction and to prevent said means being moved entirely out of said pocket when said thumb piece is moved in the opposite direction. 105

4. The combination in a flashlight having a casing, a lamp, and a battery, of a switch mechanism for controlling the flow of current through said lamp including a thumb piece slidably mounted on said casing and having a recess formed therein, a ball seated in said recess and movable with said thumb piece, a flexible circuit closing member having a pocket formed therein for co-operating with said ball and arranged to be moved into circuit closing position upon sliding movement of said thumb piece, and means for determining the extent of movement of said thumb piece in each direction to permit said ball to be moved entirely out of said pocket when said thumb piece is forced in one direction, to permanently close said circuit, and to prevent said ball being moved entirely out of said pocket when said thumb piece is moved in the opposite direction to provide for flashing operation of said lamp. 115 120 125

In testimony whereof, I have signed my name of this specification this 8th day of June, 1931.

JOSEPH F. MORAN.
